UNITED STATES PATENT OFFICE.

ANDREW STROBEL, OF ST. LOUIS, MISSOURI.

CAR-TRUCK FRAME.

1,098,463.

Specification of Letters Patent.

Patented June 2, 1914.

Application filed February 9, 1914. Serial No. 817,588.

To all whom it may concern:

Be it known that I, ANDREW STROBEL, citizen of the United States, residing in St. Louis and State of Missouri, have invented 5 certain new and useful Improvements in Car-Truck Frames, of which the following is a specification, reference being had to the accompanying drawings.

This invention relates to certain improvements in side frames for car trucks and has 10 relation more particularly to a device of this general character in which the journal boxes comprise a rigid portion formed integral with the side frame, and the principle of 15 the invention is to provide a device of this general character having novel and improved means whereby a portion of each of the journal boxes is capable of being moved or opened into an inoperative position so 20 as to permit the wheel axles to be removed without disconnecting the side frames from the other parts of the truck.

The invention consists in the details of construction and in the combination and arrangement of the several parts of my improved truck whereby certain important advantages are attained and the device is rendered simpler, less expensive and otherwise more convenient and advantageous for use, 30 all as will be hereinafter more fully set forth.

The novel features of the invention will be carefully defined in the appended claims.

In order that my invention may be the 35 better understood, I will now proceed to describe the same with reference to the accompanying drawings, wherein—

Figure 1 is a view in side elevation of a truck frame constructed in accordance with 40 my invention, with a lid of one of the journal boxes being omitted; Fig. 2 is a view in top plan of the device disclosed in Fig. 1; Fig. 3 is an enlarged sectional view through one of the journal boxes and taken longitudinally of the truck frame, the adjacent portion of the truck frame being shown in 45 fragment; Fig. 4 is a sectional view taken substantially on the line 4—4 of Fig. 3; Fig. 5 is a bottom plan view of the device 50 as illustrated in Fig. 4.

Referring to the accompanying drawings which illustrate the preferred form of my invention, A designates a cast metal side frame of any preferred design which is provided with journal boxes constructed in accordance with my invention, each of said

journal boxes consists of a rigid upper portion B that is formed integral with the side frame, and a movable lower portion or bottom C which can be opened or moved into 60 an inoperative position whenever it is desired to remove the wheel axles. The rigid portion B of the box forms the upper and major part of the box and the movable portion C the lower part or bottom of the box, 65 the division line between such parts being approximately one-quarter of the height of the box when calculated from the lower or under face thereof. The longitudinal meeting edges of such portions are substantially 70 straight but are correspondingly reduced as indicated at 1 so as to overlap in order to afford a more effective joint as is believed to be self-evident while the meeting edges of the inner end of such box are disposed 75 on vertical bevels as indicated at 2 for reasons which are believed to be self-evident. In order to give greater strength to the box and to obtain greater rigidity I find it of advantage to tie or connect the forward extremities of the side walls of the box by 80 the cross member or support 3, positioned adjacent the lower edges of such side walls, as is believed to be clearly shown. It is also to be observed that the forward face of 85 the box as determined by the support 3 is adapted to be closed by the lid 4 and the opening thereof affording a means whereby the requisite lubricant may be positioned within the box. As herein disclosed, the lid 90 4 is provided at its upper portion with the inwardly directed perforate lugs 5, through which a suitable pintle 6 is adapted to pass, said pintle being directed through the barrel 7 produced on the upper face of the 95 wall of the box.

As herein disclosed, the under portion of the frame A is reinforced by the depending webs or flanges 8, which extend entirely therealong and are formed integral with the 100 lower portion of the inner face of the wall of the journal box and these webs or flanges 8 in close proximity to the journal box, are provided with perforations 9 through which is adapted to pass a suitable pintle 10, said 105 pintle 10 being also adapted to be directed through the perforate lugs 11, herein disclosed, as formed in continuity of the reinforcing webs 12 disposed around the lower portion C whereby the same is substantially 110 reinforced, as is believed to be clearly shown in the drawings. By this arrangement it

will be seen that an effective connection is to be had between the hinged or lower portion C and the frame A. The opposite extremities of the flanges or webs 12 are projected above the opposite side of the portion 6 to afford the perforate lugs 14 adapted to register and coact with the perforate portion 15 of the webs or flanges 16 disposed around the major portion B of the journal box and disposed in substantial continuity with the upper of the reinforcing webs or flanges disposed along the upper portion of the main frame A such flanges or webs 16 being disposed in outwardly diverging planes in order that increased strength may be imparted to the portion B of the journal box.

A suitable pintle or locking pin 17 is adapted to be directed through the perforate portions 15 and the lugs 14 whereby the lower portion C or door as it may be termed, may be effectively and conveniently maintained in operative position. It is also thought to be self-evident that if desired, the pintle 17 may be employed as a hinge member in which instance, the pintle 10 may be removed. This however, is a matter of preference.

From the foregoing description, it is thought that a truck frame constructed in accordance with my invention is of an extremely simple and comparatively inexpensive nature and is particularly well adapted for use by reason of the convenience and facility with which the various parts comprised therein may be assembled and with which they may be manipulated and it will also be obvious that my invention is susceptible of considerable change and modification without material departure from the principles and spirit thereof and for this reason I do not wish to be understood as limiting myself to the precise arrangement and formation of the several parts herein shown in carrying out my invention in practice.

Having thus described the invention, what is claimed is:

1. A car truck side frame provided with a divided journal box, the division line between such parts being approximately one-quarter of the height of the box when calculated from the under face thereof, the

upper portion of the box being formed integral with the side frame, spaced reinforcing webbings disposed over the top and forward face of the upper portion of the journal box, the portions of the webbings disposed over the top of the journal box being arranged in outwardly diverging planes, the lower extremities of such webbings being perforate, a lower member hingedly connected with the frame and provided with webbings disposed therearound, such webbings terminating in projecting perforate lugs adapted to overlie the perforate extremities of the webbings of the upper portion of the box and a pintle adapted to be directed through the registering perforations for maintaining the lower portion of the journal box in operative position. 70

2. A car truck side frame provided with a divided journal box, the division line between such parts being approximately one-quarter of the height of the box when calculated from the under face thereof, the upper portion of the box being formed integral with the side frame, reinforcing webbings disposed over the top and forward face of the upper portion of the journal box, the lower extremities of such webbings being perforate, a lower member hingedly connected with the frame and provided with webbings disposed therearound, such webbings terminating in projecting perforate lugs adapted to overlie the perforate extremities of the webbings of the upper portion of the box and a pintle adapted to be directed through the registering perforations for maintaining the lower portion of the journal box in operative position, 80

the upper portion of the box being formed integral with the side frame, reinforcing webbings disposed over the top and forward face of the upper portion of the journal box, the lower extremities of such webbings being perforate, a lower member hingedly connected with the frame and provided with webbings disposed therearound, such webbings terminating in projecting perforate lugs adapted to overlie the perforate extremities of the webbings of the upper portion of the box and a pintle adapted to be directed through the registering perforations for maintaining the lower portion of the journal box in operative position, 85

the upper portion of the box being formed integral with the side frame, reinforcing webbings disposed over the top and forward face of the upper portion of the journal box, the lower extremities of such webbings being perforate, a lower member hingedly connected with the frame and provided with webbings disposed therearound, such webbings terminating in projecting perforate lugs adapted to overlie the perforate extremities of the webbings of the upper portion of the box and a pintle adapted to be directed through the registering perforations for maintaining the lower portion of the journal box in operative position, 90

the upper portion of the box being formed integral with the side frame, reinforcing webbings disposed over the top and forward face of the upper portion of the journal box, the lower extremities of such webbings being perforate, a lower member hingedly connected with the frame and provided with webbings disposed therearound, such webbings terminating in projecting perforate lugs adapted to overlie the perforate extremities of the webbings of the upper portion of the box and a pintle adapted to be directed through the registering perforations for maintaining the lower portion of the journal box in operative position, 95

In testimony whereof I hereunto affix my signature in the presence of two witnesses.

ANDREW STROBEL.
